FLEXIBLE CLAMP FOR JEWELRY PARTS

William H. Hatch, Pittsburg, Calif.

Application August 19, 1952, Serial No. 21,108

Term of patent 14 years

(Cl. D54—14)

To all whom it may concern:

Be it known that I, William H. Hatch, a citizen of the United States, residing at Pittsburg, in the county of Contra Costa and State of California, have invented a new, original, and ornamental Design for a Flexible Clamp for Jewelry Parts, of which the following is a specification, reference being had to the accompanying drawing, forming a part thereof.

Fig. 1 is a side elevational view of a flexible clamp for jewelry parts, showing my new design; the opposite side of the clamp presenting substantially the same appearance.

Fig. 2 is a top plan view of the flexible clamp.
I claim:

The ornamental design for a flexible clamp for jewelry parts, as shown and described.

WILLIAM H. HATCH.
